UNITED STATES PATENT OFFICE.

JOHN W. WHITESIDE, OF NEW YORK, N. Y.

CLEANER.

Application filed February 7, 1922. Serial No. 534,734.

To all whom it may concern:

Be it known that I, JOHN W. WHITESIDE, a citizen of the United States, residing at New York city, county of New York, and 5 State of New York, have invented certain new and useful Improvements in Cleaners, fully described and represented in the following specification and the accompanying drawings, forming a part of the same.

10 This invention relates to improvements in clothes line cleaning devices, and particularly to that class of such devices as the double pulley type secured adjacent to a house and running thence to a pole in the 15 house yard, which device will be capable of being readily applied to and removed from such pulley clothes lines.

One of the objects of this invention is the provision of a device which will be simple, 20 cheap and easy of application and removal, and that will keep the upper line of such a double pulley line clean, so that if clean clothes hanging on the lower line to be dried come in contact with such upper line 25 through being blown against it, or otherwise, such clean clothes will not be soiled.

In the accompanying drawings forming part of this application,—

Figure 1 is a side view of the device as applied to a double pulley clothes line, and 30

Figure 2 is a cross sectional view thereof.

Referring to the drawings, A and B are cylinders or tubes, which will preferably be composed of light metal capable of being 35 struck into shape at one operation and preferably divided into substantially equal parts longitudinally, hinged at C and provided with means for maintaining such two parts in closed relation. The main purpose of 40 tube A is to carry suitable cleaning material D of clean rag or other material suitable for cleaning the clothes line F, which cleaning material will be of such character that it will be sufficiently soft to enter and clean between the strands of the clothes line without leaving lint or other objectionable elements on such line, and held against withdrawal from said tube by pins E, as shown, or in any other suitable manner, and said 45 tube should therefore be somewhat larger in internal diameter than the line F to which it is to be applied, to admit of carrying said cleaning material therein. The tubes A and B will preferably be so joined together that 50 when in position movement of tube B (which may be termed the controlling tube)

will cause movement of the other tube in the same direction. Any suitable means may be provided for causing such dual movement, as connecting arm G. This arm G will preferably consist, as shown, of a strip of metal similar to that of tubes A, B, in any suitable form and preferably provided with suitable lugs H at each end, adapted for connection to the corresponding tube in any suitable 60 manner, as by rivets, so that it will be adapted to cooperate with suitable parts of said tubes, as shown. This arm will also aid in preventing twisting of the clothes lines whether the lines are in use or not. 65

Tube B will preferably be somewhat flattened, as shown, or otherwise suitably shaped in order to furnish proper gripping surface for clothes line F to prevent said tube being carried along the clothes line to 70 which it is attached and also to prevent the line moving through such tube. Tube B will preferably also be somewhat longer than tube A to provide for greater stability 75 of the device and it will preferably also be 80 smaller in internal diameter than tube A, since the latter carries no cleaning material. The tubes A and B will preferably be provided with hinges of any suitable construction, as C, to permit of their ready application to, and their ready removal from, a 85 clothes line.

I have found in practice that with tube A about $3\frac{1}{2}$ " long, tube B should be about $5\frac{1}{2}$ " long, and the diameter $\frac{1}{2}$ " and $\frac{3}{8}$ " respectively. 90

The tubes A and B will be provided with suitable means for maintaining them in closed position, that shown being preferred and consisting of arm I, pivoted through 95 post J on the connecting arm G and held in position by screw K, said arm having at one end an operating handle M, to press the spring L which normally maintains the tube parts in closed position, one end of said 100 spring being suitably secured to handle M and its opposite end unsecured, but limited in its movement and also that of said handle by stop P on connecting arm G. A lug N will be provided on the opposite end of arm I in 105 order that it may be adapted to cooperate with lug Q on overhanging arm O on each of the tubes A, B, preferably through the oppositely inclined contact surfaces on said lugs.

110 While the device is simple and it is believed its operation will be readily under-

stood from the foregoing, a short description of the operation thereof will now be given. The tubes are opened when the latches are relieved from pressure of springs 5 L by force applied to handle M. A length of cleaning material will then be applied to the upper clothes line F of the pair of pulley lines to be cleaned, when the upper tube A will be closed to surround the upper line (to 10 which the cleaning material has been applied) and the two parts of the tube then so closed that the pins E will grip the cleaning material, (if applied direct to the clothes line) and in such manner that the lug N will 15 take under lug Q on arm I and be held in that position by spring L. Tube B will then be closed to surround and be held on the lower clothes line in the same manner, the pins therein gripping said line to cause 20 the tubes to move therewith. The line will then be pushed or pulled (depending on whether the upper or lower line is used for the purpose) to send the device to the pole end, where it will remain until it is desired 25 to recover it for renewal of cleaning material, repairs, or for other purposes, when the line will be pushed in the opposite direction to that used for sending it out, and the operation of applying the tubes and 30 cleaning material reversed in order to remove it from the line.

It will be understood that various changes may be made in the specific construction of the mechanism employed for carrying out the invention, and that the invention is not 35 to be restricted to the precise details of construction shown and described.

What I claim is:

1. A device of the class described comprising a tube carrying clothes line cleaning means, a second tube rigidly connected with the first tube and adapted to engage and be moved with the movement of a clothes line. 40
2. A device of the class described comprising a tube carrying clothes line cleaning means, a second tube rigidly connected with the first tube, and adapted to be moved with the movement of a clothes line, said tubes being provided with closing means. 45
3. A device of the class described comprising a longitudinally divided cylinder or tube provided with means for carrying a line cleaning material, a second tube connected to said first tube and similarly divided and formed to prevent free movement longitudinally of the rope both tubes being 50 provided with closing means. 55

In testimony whereof, I have hereunto set my hand.

JOHN W. WHITESIDE.
